UNITED STATES PATENT OFFICE

167,827

ROSARY MEDAL

Damon M. Doherty, St. Cloud, Minn.

Application October 29, 1951, Serial No. 17,156

Term of patent 14 years

(Cl. D29—2)

To all whom it may concern:

Be it known that I, Damon M. Doherty, a citizen of the United States of America, residing at St. Cloud, Minnesota, have invented a new, original, and ornamental Design for a Rosary Medal, of which the following is a specification, reference being had to the accompanying drawing, forming a part hereof.

Fig. 1 is a front elevational view of a rosary medal showing my new design; and

Fig. 2 is an edge view thereof.

The back of the article shown in Fig. 1 is plain.
I claim:

The ornamental design for a rosary medal, substantially as shown.

DAMON M. DOHERTY.
